UNITED STATES PATENT OFFICE.

WILLIAM COONAN, OF JERSEY CITY, ASSIGNOR TO HIMSELF, AND WM. A. CHILDS, OF ENGLEWOOD, NEW JERSEY.

TELEPHONE SYSTEM.

SPECIFICATION forming part of Letters Patent No. 537,967, dated April 23, 1895.

Application filed August 4, 1892. Serial No. 442,131. (No model.)

To all whom it may concern:

Be it known that I, WILLIAM COONAN, a subject of the Queen of Great Britain, residing at Jersey City, in the county of Hudson and State of New Jersey, have invented certain new and useful Improvements in Telephonic Systems, of which the following is a full, clear, and exact description.

This invention relates to telephonic systems, and has special reference to means whereby the operator at the exchange may determine whether a subscriber called for is busy or not. This operation is commonly known as "testing," and many different ways of making this test have been devised.

The object of my invention is to provide a test in which the indication of "busy" or "free" is made by an instrument having no effect upon the subscriber's line.

A further object of the invention is to provide a test apparatus which is simple, quick and easy to manipulate.

The invention consists of the method and details of construction which will be herein-after described and claimed.

In the accompanying drawings, Figure 1 represents a diagram of the circuits. Fig. 2 represents an external view of the circuit controller to be held in the hand of the operator. Fig. 3 represents a longitudinal section of one end of the circuit controller. Fig. 4 is a transverse section of the same taken on line *a*—*b* of Fig. 2. Fig. 5 is a similar section taken on line *c*—*d* of Fig. 2. Fig. 6 is a side elevation of the test magnet.

Referring to the drawings by letters and figures, A represents a magneto generator.

B represents a test magnet. It consists of two magnets *b* and *b'* respectively acting in opposition to each other upon an armature *b*² pivoted in the middle at *b*³. The number of turns and size of wire on the magnet *b* is such as to give it about one hundred ohms resistance, and the number of turns on magnet *b'* is such as to give it about twelve hundred ohms resistance. In series with the magnet *b'* is a further artificial resistance of say four thousand eight hundred ohms. A spring *b*⁴ acts upon the armature *b*² in opposition to the high resistance magnet *b'*.

C is a handle of hard rubber or other insulating material which is held in the exchange operator's hand. This handle is provided on its under side with a longitudinal groove *c*, in which is placed a key *c'* hinged at the point *c*² and carrying a brass strip *c*³ which projects at one end and carries two contact points as shown. A spring *c*⁴ bears against the back of the key with a tendency to force it outward. Two stops or contacts *c*⁵, *c*⁶ respectively are fixed in the end of the handle, and are provided with suitable means for connecting electrical conductors, and forming circuit terminals with which the end of strip *c*³ is adapted to engage. Two conductors 12 and 1 connected together in a flexible cord *c*⁷ lead respectively from these terminals to the operator's speaking instrument D and the magneto generator A. At the opposite end of the handle two other conductors 8 and 10 located together in a flexible cord *c*⁸ pass through suitable openings in the end of the handle, and in the key, and lead out through a hole *c*⁹ in the face of the key to the two points of a double contact plug I. The cord connecting the handle to the plug is short, so that the plug is within easy reach and may be held by the fingers of the hand which grasps the handle. The two conductors 8 and 10 lead back from the plug to the magnets *b* and *b'* respectively. The two flexible cords *c*⁷ and *c*⁸ are joined together in a single flexible cord *c*¹⁰, and thence pass to the different points mentioned. The brass strip *c*³ is connected to wire 10 by the short wire *c*¹¹.

D represents the operator's speaking instruments which are connected on one side by wire 12 with the contact point *c*⁵ in the handle and on the other side by wire 13 with wire 8 leading to one of the contacts in plug I.

The operation is as follows: When a subscriber calls for a connection, central operator puts plug I into a socket of the switchboard corresponding to the subscriber wanted, and squeezes key *c'* in. This socket is represented in Fig. 1 by *e*, and it contains two contact pieces forming the terminals of the subscriber's circuit. The two terminals of the plug make contacts respectively with the terminals of the subscriber's circuit and

establish the following path for the magneto current generated by A: from generator A by wire 1, contact c^6 , strip c^8 , to the point 2 where it divides, a portion going by wire 3, 5 plug and socket, called subscriber's wire 4, and, when the called subscriber's telephone is on the hook, or is in its normal position, the current flows through wire 5, bell magnet 6, artificial resistance of about fifteen hundred 10 ohms, subscriber's hook switch, wire 7, plug e , wire 8, test magnet b , wire 9 to the generator. From the point 2 where the current divides, the other portion flows over the wire 10, test magnet b' , wire 11 and generator. 15 Now, the subscriber's bell magnet 6 and the artificial resistance, being in circuit and adding a large resistance to the line, there will be a comparatively small amount of current flowing through the test magnet b , and therefore 20 a comparatively large amount of current flowing through test magnet b' . In fact these magnets are wound so that when the subscriber's circuit and bell magnet are in circuit the ampère-turns of test magnet b will be less than the ampère-turns of test magnet b' . 25 Consequently b' will pull down the armature with each impulse of current, and between the impulses the spring b^4 will pull the armature in the opposite direction, the result being 30 a fluttering or buzzing of the armature b^2 . This fluttering which is audible to the operator is the indication to her that the called subscriber's line is free. Operator then releases key c' , which puts her telephone into circuit 35 with the called subscriber. When subscriber answers operator may connect the two subscribers together by any means at her disposal. In case the called subscriber is already connected with any other subscriber on 40 the switchboard, then the joint resistance of the two lines, being much lower than the resistance of either one of them, more of the current will flow from the point 2 over the subscriber's lines and through the test mag-

net b , so that the ampère-turns of b will be 45 more than those of b' . b then acting in conjunction with the spring b^4 , will attract the armature and hold it stationary. "Silence" will therefore be the indication to the operator that the called subscriber is busy. It will 50 be observed that this test is made without the use of the speaking instruments and the loud and objectionable "click" or noise which is caused by a battery current acting upon the calling subscriber's receiver is therefore 55 not experienced. The line itself is used as part of the test circuit, and the whole apparatus is simple, and quickly and conveniently operated.

Having thus described my invention, I 60 claim—

1. In telephone exchange systems, a testing apparatus consisting of two electro-magnets of different resistances, connected in parallel and acting in opposition upon a pivoted armature, in combination with a switching apparatus and a subscriber's line, said switching apparatus being arranged to connect the subscriber's line in series with one of said magnets, substantially as described. 70
2. In telephone exchange systems, the combination with a subscriber's line, an artificial resistance and a bell magnet therein at subscriber's station, a switch arranged to cut said resistance out and leave the line closed, a central office testing apparatus consisting of two electro-magnets of different resistances, connected in parallel, an operator's switching apparatus and means whereby the subscriber's line may be connected in series with one of 80 said magnets, substantially as described. 75

In testimony whereof I subscribe my signature in presence of two witnesses.

WILLIAM COONAN.
